GARMENT SNAP

Therese Stanchfield, Los Angeles, Calif., assignor
of one-half to Marcia W. Samelson and Edgar
M. Samelson, Roscoe, Calif.

Application July 2, 1938, Serial No. 217,306

2 Claims. (Cl. 24—108)

This invention relates to a two-part snap clasp which is adapted to attach two pieces of fabric to each other and which also has other uses.

Among the objects of the invention are to 5 simplify snap clasp structures in certain particulars and also to provide a structure of this kind which will be adapted for a greater variety of uses.

A more specific object of the invention is to 10 provide a fastener of the type stated which is formed to be impaled upon a wooden or other like support for the purpose of securing garment or other article to such a support.

Still other objects, advantages and features of 15 the invention may hereinafter appear.

Referring to the accompanying drawing, which illustrates what is at present deemed to be a preferred embodiment of the invention,

Fig. 1 is a plan view of the complete clasp, 20 the female member thereof being uppermost.

Fig. 2 is a vertical mid-section taken on line 2—2 of Fig. 1.

Fig. 3 is a transverse section on line 3—3 of Fig. 2.

Fig. 4 is a fragmental vertical mid-section of 25 a modification of the invention, showing the same on an enlarged scale in order to illustrate certain details of construction more clearly.

Referring in detail to the drawing, the female 30 member of the clasp comprises a disk 10 having a hollow dome shaped central portion 11 and a peripheral flange 12 which is curled over inwardly a sufficient distance to retain a sinuous wire spring 14 which serves as a means for detachably retaining the female member in its 35 secured position in relation to the head 15 of the male member.

Said spring 14 has an arcuate central portion 16 rebent inwardly at each end at 17 and thence 40 continued as a substantially straight intermediate run 18 which, in turn, is rebent at 19 and thence continued as a substantially straight terminal run 20, said terminal run being longer than said intermediate run 18. When the male and female members are united to each other 45 the runs 20 of the spring 14 are substantially parallel.

The dome portion 11 of the female member has diametrically opposite segmental slots 25 cut 50 through its basal portion, said slots being sufficiently wide to permit the terminal spring portions 20 to grip between them the neck portion 26 of the head of the male member, just below the annular shoulder 30 resulting from the circumferentially outswelled portion 27 of the head

15. Said head is furnished at its top with a point portion 28 adapted to pierce readily through fabrics to which the clasp is applied.

The neck 26 of the male member upstands 5 from a basal disk 29 around and beneath which extends a backwardly bent flange 30.

In Fig. 2, superimposed sheets 31 and 32 are shown secured together by the clasp.

In Fig. 4 the neck and head of the male member of the clasp is shown on an enlarged scale 10 in order to illustrate more clearly certain details included in the invention. In this view the head 15 is shown having an angular peripheral extremity 33 above which is the conically concaved pointed portion of the head and below 15 which is the annular slightly convexed shoulder 27. The convexity of said shoulder causes an additional initial resistance to be offered to withdrawing the two members of the clasp from each other in opposition to the spring 14, but causes 20 a quick release to occur as soon as said spring has passed the most outswelled part of said convexity.

The conically concaved shape of the head of the male member slenderizes the pointed portion 25 thereof and causes good initial penetration thereby of any fabric which it may be used to puncture, followed by an efficient widening out of the hole made by the point. The neck 26 of the male member is somewhat tapered so that 30 its basal portion is materially greater in diameter than its outer portion, thus adding to its strength and making it easier to manufacture.

In the modification shown in Fig. 4 an impaling member 35 is shown, which has been inserted from the interior of the female dome 11 through an aperture 36 provided therefor through the top of said dome. Said impaling member 35 may be a nail, screw or tack. It has a head 37 the diameter of which is greater than the 40 diameter of the aperture 36. Said impaling member is shown having in its headed end portion a central recess 38 which is sufficiently deep and narrow to guard against the point of the head of the male member becoming blunted. 45 Said impaling member 35 is shown penetrating a support 39.

The male member of the device is shown provided with a set of apertures 40, and the female member with apertures 41, through which stitches 50 or other fastening means are passed to secure the two parts of the clasp to garments or other articles.

I claim:

1. In a snap structure, two separable members, 55

one a male member and the other a female member, said male member having a head carried by a neck portion and said female member having means to resiliently grip said neck portion adjacent to said head, said head having an annular convexly shouldered portion directed toward said neck to offer additional initial resistance to the separation of the two members of said clasp and a quick release as said gripping means passes over the outer part of said convexly shouldered portion, said gripping means consisting of spring wire portions transverse to the axis of said neck positioned to bear laterally against said neck and shouldered portion.

2. In a snap structure, two separable members, one a male member and the other a female member, said male member having a head carried by a neck portion and said female member having means to resiliently grip said neck portion adjacent to said head, said head having a pointed portion which is slenderized by being conically concaved whereby initial penetration of a fabric thereby is facilitated followed by an increased widening of the aperture made in the fabric by said pointed portion. 5

THERESE STANCHFIELD.
